UNITED STATES PATENT OFFICE.

HENRY F. WOLNICK AND RICHARD HERVIG, OF CHICAGO, ILLINOIS, ASSIGNEES TO
AMERICAN CAR AND FOUNDRY COMPANY, OF ST. LOUIS, MISSOURI, A CORPORA-
TION OF NEW JERSEY.

AUTOMATIC CHUCK.

Application filed December 29, 1919. Serial No. 348,167.

To all whom it may concern:

Be it known that we, HENRY F. WOLNICK
and RICHARD HERVIG, residing at Chicago,
Cook County, Illinois, and being citizens of
5 the United States, have invented certain
new and useful Improvements in Automatic
Chucks, of which the following is a full,
clear, and exact description, such as will en-
able others skilled in the art to which it ap-
10 pertains to make and to use the same, refer-
ence being had to the accompanying draw-
ings, which illustrate the preferred form of
the invention, though it is to be understood
that the invention is not limited to the exact
15 details of construction shown and described,
as it is obvious that various modifications
thereof within the scope of the claims will
occur to persons skilled in the art.

In said drawings:

20 Figure 1 is a view, partly in elevation and partly in central vertical section, of our improved chuck, the end of a grooved shank drill being shown in position in the chuck.

Figure 2 is a view, partly in elevation and partly in central vertical section, the plane of the section being at right angles to the plane of the section of Fig. 1.

Figures 3, 4, 5 and 6 are sections taken on lines 3—3, 4—4, 5—5 and 6—6, respectively of Fig. 1.

Figure 7 is a section taken on line 6—6 of Fig. 1 with the chuck shown in the release position.

Figure 8 is a view in elevation of the 35 chuck body, the body being partly broken away so as to show the spring slot.

Figure 9 is a view in elevation of the jaw retainer of the chuck.

Figure 10 is a view of the jaw retainer of the chuck taken at right angles to Fig. 9, and Fig. 11 is a view of a modified form of the chuck adapted to be screwed onto the driving spindle.

It is an object of our invention to provide
45 an improved chuck for holding grooved
shank twist drills of the type wherein the
drill retaining jaws are forced to retaining
position by cams as the chuck is moved to
operative position and the jaws are spring
50 operated to release position in the inopera-
tive position of the chuck, the cams being
then so positioned as to release the jaws.

It is also an object of our invention to provide an improved chuck that may be readily operated manually to the inoperative posi-

tion and which will automatically return to the operative position when released in any other position.

With these and other objects in view our invention comprises, as shown in Figs. 1 and 2, a tapered stem 1, adapted to be inserted in the spindles of lathes or other machines in the place of the usual tapered stems of twist drills. The stem 1 is provided with a head 2 having a flange 3, interiorly screw threaded, and a projection 4 provided with a tapered hole for the reception of the tapered end of the drill. 60 65

Screw threaded to the flange 3 is the sleeve 5, the outer face of the sleeve being cylindrical while the opposite sides of the inner face of the sleeve have the cam surfaces 6 and 7 shown in Figs. 3 to 7. Screw threaded to the outer end of the sleeve 5 is the cap 8.

Within the sleeve 5 and engaging cap 8 is the jaw retainer 9, shown separate in Figs. 9 and 10. The jaw retainer 9 is substantially cylindrical in shape, and has a shoulder 10 at its lower end that engages the cap 8, recesses 11 and 12 to receive the springs that move the jaws to the release position, a groove 13, at the center to receive the main operating spring, a pair of diametrically opposed slots 14 and 15 at each end to receive the projections at the ends of the jaws 16 and 17 and a screw threaded opening 48. The jaws 16 and 17 lie within the sleeve 5.

The jaws 16 and 17 lie within the jaw retainer 9, and each has a body extending lengthwise of the jaw retainer and shaped to fit the grooves of the drill shank and at each end of the jaw body is a projection, as 27 and 28 in Fig. 2, rectangular in shape and extending at right angles to the jaw body through the recesses 14 and 15 of the retainer 9, the outer ends of the projections engaging with the cam faces 6 and 7. In the recesses 11 and 12 and engaging in openings in the ends of the jaws are springs 18 and 19 adapted to retract the jaws 16 and 17 when they are not forced inwardly by the cam surfaces 6 and 7. Lying in the groove 13 and having its ends engaging in the slot 20 in the jaw retainer 9 and in the slot 21 in the sleeve 5 is a spiral spring 22, of several turns, that surrounds the jaw retainer 9 and serves to maintain the jaw retainer 9 in such position, relative to the sleeve 5, that the cam surfaces 6 and 7 will be effective to force the jaws 16 and 17 inwardly to operative position. Surrounding the sleeve 5 and engag- 110

ing the cap 8 and the flange 3 of the head 2 is a knurled sleeve 23. A pin 24, passes through an opening 25 in the knurled sleeve 23, through a slot 26 in the sleeve 5 and is secured in the screw threaded opening 48 in the jaw retainer 9.

To operate the device when it is mounted upon a lathe or other machine that will serve to hold the stem 1, head 2 and sleeve 5 against rotation, the knurled sleeve is rotated approximately a quarter-turn, and rotates the jaw retainer 9 by means of pin 24, the pin 24 travelling freely in the slot 26 of sleeve 5. This rotates the jaw retainer 9 to a position in which the projections 27 and 28 are opposite the parts of the cam faces that are furthest from the central axis of the chuck, thus permitting the jaws 16 and 17 to be retracted by the springs 18 and 19 for the insertion or withdrawal of the drill, and tightens the windings of spring 22. Upon release of the knurled sleeve, the spring 22 rotates the jaw retainer 9 and knurled sleeve 23, and the cam faces 6 and 7 act upon the projections 27 and 28 and the jaws 16 and 17 are forced inwardly, against the action of springs 18 and 19, into tool engaging or normal position.

In the modification shown in Fig. 11, the head 2, instead of being attached to a tapered stem 1 as in Fig. 1, is provided with an interiorly screw threaded flange 30 so that the chuck may be attached to the spindle of the lathe or other machine.

What we claim is:

1. A chuck comprising a head, a sleeve having cam faces carried by the head, a jaw retainer having slotted ends mounted in said sleeve and rotatable with respect to said head, U-shaped jaws mounted in said slots in said jaw retainer and having their ends engaging said cam faces and yielding means to cause said cam faces to operate said jaws.

2. A chuck comprising a head, a sleeve carried by said head, a jaw retainer having slotted ends in said sleeve, U-shaped jaws having their ends engaging in the slots in said jaw retainer, a cap carried by said

sleeve and engaging said jaw retainer and means engaging said head and said cap 50 for operating said jaw retainer.

3. A chuck comprising a head, a sleeve having cam faces carried by said head, a jaw retainer having slotted ends in said sleeve, U-shaped jaws carried by said jaw 55 retainer and having their ends projecting through the slots in said jaw retainer and engaging said cam faces, a groove in said jaw retainer and a spring mounted in said groove and adapted to hold said sleeve and 60 jaw retainer in normal relative positions.

4. A chuck comprising a head, a sleeve carried by said head, a jaw retainer, slotted at its ends, within said sleeve, U-shaped jaws having their ends engaging in the slots in 65 said jaw retainer and a second sleeve surrounding said first sleeve and adapted to operate said jaw retainer.

5. A chuck comprising a head, a slotted sleeve carried by said head, a jaw retainer 70 in said sleeve and having slotted ends and a circumferential groove between the slots, jaws having their ends in the slots in said retainer, a spring in said groove and engaging said slotted sleeve and said jaw retainer, 75 a second sleeve surrounding said slotted sleeve and a connection between said second sleeve and said jaw retainer extending through the slot in said first sleeve.

6. A chuck comprising a head, a slotted sleeve carried by said head, a jaw retainer having slotted ends in said sleeve, U-shaped 80 jaws having their ends engaging in the slots in said jaw retainer and contacting with said slotted sleeve, a second sleeve surrounding 85 said first sleeve and a connection between said jaw retainer and said second sleeve extending through the slot in said first sleeve.

In witness whereof we have hereunto set our hands in the presence of two witnesses. 90

HENRY F. WOLNICK.
RICHARD HERVIG.
